UNITED STATES PATENT OFFICE.

JOSEPH HERRBURGER, OF PARIS, FRANCE.

PIANO-ACTION.

SPECIFICATION forming part of Letters Patent No. 520,989, dated June 5, 1894.

Application filed April 4, 1894. Serial No. 506,249. (No model.)

To all whom it may concern:

Be it known that I, JOSEPH HERRBURGER, of Paris, France, have invented an Improved Piano-Action, of which the following is a specification.

This invention relates to an improved action for grand pianos and more particularly to an improved construction of the spring and of the finger which operates the hammer.

10 In the accompanying drawings: Figure 1 is a side elevation of my improved piano action; Fig. 2 a top view of the repeating lever and finger, and Fig. 3 a bottom view of the repeating lever.

15 Heretofore it has been the general practice to attach the spring in grand actions to the rider flange *f*. The objections to this construction are that the spring during use produces a friction against the repeating lever

20 *l*, and also that the tension of the spring is regulated with difficulty. I propose to attach the spring *r*, not to the rider flange at all, but directly to the repeating lever. To this effect the repeating lever is provided with a pair of

25 downwardly depending flanges or cheeks *l'*, between which a slot is formed. This slot is bridged by a pin *m*, around which the spring *r*, is bent. From this pin the spring extends directly to the jack, it being coiled preferably

30 as at *r'*, in order to obtain greater elasticity. The spring operates upon the jack *e*, with its lower end, while with its upper end it operates upon the lever *l*. Owing however to the fact that the spring is fastened directly to the

35 lever, the pressure on the latter is produced without the least friction. Through the lever *l* extends the regulating screw *v*, that bears upon the spring and by which the ten-

sion of the spring may be readily adjusted. With actions that use a pivoted finger above 40 the repeating lever, to transmit motion to the hammer shank, it has been the custom to pivot such finger to the rider flange. I propose to pivot the finger, not to the rider flange, but to the repeating lever. To this effect the 45 lever *l* is provided with a perforated projection *n*, that enters a slot *n'* of the finger *p*, and is connected thereto by a pivot *n''*. The advantage connected with this construction is that I avoid any friction arising from any 50 difference of motion between the repeating lever and the finger.

What I claim is—

1. A grand piano action provided with a bent spring, which is fastened to the repeating lever and extends directly from said lever to the jack, substantially as specified.

2. A grand piano action provided with a slotted repeating lever, a regulating screw engaging the same, and a bent spring which is 60 fastened to the repeating lever and extends directly from said lever to the jack, substantially as specified.

3. A grand piano action provided with a repeating lever and with a finger pivoted directly to said lever and adapted to engage the hammer-shank, substantially as specified.

4. A grand piano action provided with a repeating lever having an upwardly extending projection, and with a slotted finger pivoted 70 to said projection and adapted to engage the hammer-shank, substantially as specified.

JOSEPH HERRBURGER.
